CLAIM

I claim the ornamental design for a façade panel, as shown and described.

DESCRIPTION

FIG. 1 is a front perspective view of a façade panel of the present invention;

FIG. 2 is a rear perspective view of a façade panel of the present invention;

FIG. 3 is a front view of a façade panel of the present invention;

FIG. 4 is rear view of a façade panel of the present invention;

FIG. 5 is a left side view of a façade panel of the present invention;

FIG. 6 is a right side view of a façade panel of the present invention;

FIG. 7 is a top view of a façade panel of the present invention;

FIG. 8 is a bottom view of a façade panel of the present invention;

FIG. 9 is an enlarged upper right hand side of the upper shoulder of a façade panel of the present invention shown in FIG. 1; and,

FIG. 10 is an enlarged front view thereof.

The broken lines in the figures are for contextual purposes or show the environment and form no part of the claimed design.

The portion between the dot dash broken lines in the drawings are broken away to indicate no particular length or width of the façade panel and such pairs of dot dash broken lines themselves form no part of the claimed design. The material that may be visible between the dot dashed broken lines has been removed for clarity. The façade panel is of indefinite height and width as shown by dot dashed break lines in the drawings.

1 Claim, 7 Drawing Sheets
